D. J. HIGGINS

GLASS HEATER

Filed July 11, 1924

Fig. 2.

Daniel J. Higgins,
INVENTOR

BY *Victor J. Evans*

WITNESS: *Gerald Kennedy*

ATTORNEY

UNITED STATES PATENT OFFICE.

DANIEL JOSEPH HIGGINS, OF JAMAICA PLAIN, MASSACHUSETTS.

GLASS HEATER.

Application filed July 11, 1924. Serial No. 725,485.

To all whom it may concern:

Be it known that I, DANIEL J. HIGGINS, a citizen of the United States, residing at Jamaica Plain, Boston, in the county of 5
5 Suffolk and State of Massachusetts, have invented new and useful Improvements in Glass Heaters, of which the following is a specification.

This invention relates to a heater, the 10 general object of the invention being to provide means whereby glass rods can be heated while being held in suspended condition so that the rods can be bent into ring or other shapes. 15 This invention also consists in certain other features of construction and in the combination and arrangement of the several parts, to be hereinafter fully described, illustrated in the accompanying drawings and 20 specifically pointed out in the appended claims.

In describing my invention in detail, reference will be had to the accompanying drawings wherein like characters denote like 25 or corresponding parts throughout the several views, and in which:—

Figure 1 is an elevation of the invention. Figure 2 is a plan view thereof.

In these views, 1 indicates a cylinder 30 which is supported upon the base 2 and which is provided with the double coupling 3 so that air and gas can be introduced into the same through tubes or the like attached to suitable sources of supply. Each part 35 of the coupling is provided with a cock 4. Vertical pipes 5 have their lower ends supported by the top of the cylinder and these pipes are in communication with the interior of the cylinder. Each pipe is provided 40 with a row of perforations, as shown at 6, the perforations being arranged on the inner side of the pipe so that the flames resulting from the burning products of combustion escaping through the perforations 45 will be directed inwardly into the space formed by the pipes 5. A plate 7 is sup-

ported by the tops of the pipes and this plate is provided with a central hole 8 through which a rod of glass to be treated passes into the space between the pipes. 50 This rod is supported by the spring holder 9 which is formed on the horizontal arm 10 of the upright 11, this upright 11 being adjustably supported on the upright 12 by the bolts 13, the upright 12 being connected 55 with the cylinder.

From the foregoing it will be seen that a rod suspended from the arm 10 and passed through the hole 8 in the plate 7 will have that part which is located in the space 60 formed by the pipes 5 subjected to the impinging flames and thus will be softened so that it can be readily bent as desired. By making the holding means adjustable rods of different lengths can be treated. 65

It is thought from the foregoing description that the advantages and novel features of my invention will be readily apparent.

I desire it to be understood that I may make changes in the construction and in the 70 combination and arrangement of the several parts, provided that such changes fall within the scope of the appended claims.

What I claim is:—

1. A device of the class described comprising a cylinder, vertically arranged burner tubes supported on the cylinder, means for holding an article to be treated between the burners and means for supplying fuel to the cylinder. 75

2. A device of the class described comprising a cylinder, vertically arranged burner tubes thereon, a plate connecting the upper ends of the tubes together, said plate having a hole in its center, an adjustable 80 support carried by the cylinder and having a laterally extending part positioned over the plate, holding means on said part and means for supplying fuel to the cylinder. 85

In testimony whereof I affix my signature.

DANIEL JOSEPH HIGGINS.
